INTERFITTING METAL AND WOODEN PARTS
PARTICULARLY IN GUN MAKINGWoodrow W. Henry, Granby, Mass., assignor to Savage
Arms Corporation, Chicopee Falls, Mass., a corpora-
tion of Delaware

Filed Nov. 4, 1957, Ser. No. 694,208

4 Claims. (Cl. 29—424)

The present invention relates to the art of interfitting wooden and metal parts and finds particular utility in the art of gun making.

One of the most difficult tasks of interfitting wooden and metal parts is found in the manufacture of a widely used type of rifle. In this rifle both the receiver and the stock are provided with a pair of tangs which are interdigitated in assembly. Such assembly is conventionally a tedious operation requiring great skill in fitting (by filing, sanding, etc.) the matching surfaces of the pieces. It is obvious that, under practical manufacturing conditions, cracks will be found between the interdigitated parts and these cracks can be so unsightly as to require the parts to be reworked or rejected entirely. An even worse result is that the interdigitated tang portions may be imperfectly seated and make endwise contact at only one or two localized points. Theoretically a four point bearing or seating between the stock and the receiver is necessary to properly distribute the shock transmitted to the stock each time the gun is fired. As noted, this four point bearing cannot be obtained with any predictable reliability by conventional assembly methods with the result that as many as 12% of the stocks split when the guns have been test fired prior to sale. Since in any event this type of defect cannot be discovered until the guns are at least substantially complete, a number of defective parts represents a very substantial loss, particularly in terms of labor spent on the defective stock itself and on salvaging the metal parts for future use.

One object of the present invention is to eliminate the need for manually and individually removing high and low spots to interfit wooden and metal parts and to increase the speed and accuracy with which such parts may be interfitted.

Another object is to increase the speed and accuracy with which gun stocks may be assembled.

A further object is to assure a four point bearing between interdigitated tangs of receivers and stocks thereby minimizing if not eliminating stock breakage upon firing of the guns.

The invention will be found in various novel steps including forming the wooden part to the approximate shape of the metal part which is to be seated therein or thereon but in such a fashion that a relatively small amount or layer of wood interferes with the proper interfitting of said parts. The metal part, heated to between 700° F. and 900° F., is then forceably joined to interfit the metal part on the prepared seat whereby the interfering wood will be displaced and compacted.

The above mentioned temperature range is sufficiently high to actually cause charring or carbonization of the wood and therefore, especially in gun receivers, it is preferable to take the additional step of introducing a char retarding agent on the prepared seat prior to forcing the seated metal part thereon.

The above and other related objects and features of the invention will now be described in greater particularity with reference to the accompanying drawing and the novelty thereof distinctly pointed out in the appended claims.

In the drawings—

FIG. 1 is a perspective view, with certain portions

2

broken away and in section, of an industrial electric oven which can be employed in heating metal receivers;

FIG. 2 is a perspective view, partly in section and on a greatly enlarged scale, of a receiver and gun stock aligned for interdigital interfitting of tang portions;

FIG. 3 is an elevation of a jig and fixture suitable for forceably interfitting the illustrated stock and receiver of FIG. 2;

FIG. 4 is a section, on an enlarged scale, taken on line IV—IV in FIG. 3; and

FIG. 5 illustrates the relative degree of interference on a portion of the seat prepared on the gun stock with the matching portion of the receiver frame.

The following disclosure deals with the interfitting of 15 a gun stock and receiver (frame portion only) of a well known type and while the inventive steps herein outlined have particular novel features pertinent to such stocks and receivers it will be apparent that the utility of the invention as a whole is not so limited and in fact may 20 well be practiced outside the art of gun making.

Referring to FIG. 2, 10 indicates a receiver frame having tangs 12, while 14 depicts a gun stock having tangs 16 (see also FIG. 4). At this point note can be taken that the tangs 12 are of unequal length with the lower 25 tang being the longer, while the tangs 16 are of equal length. These proportions are well established by the functional design of the gun and have nothing to do with the present invention other than to illustrate one of the more difficult interfitting operations.

30 It is preferable that, prior to interfitting, the gun stock be in a rough finished stage. This means, among other things that its shape will approximate that of a finished stock but that all of its exterior dimensions will be oversize. Of greater importance to the present invention the 35 socket between the tangs 16, which serves as a seat for the tangs 12, is formed undersize. In other words there is an interference of material which prevents a free interfitting of the two parts. This condition is best illustrated in FIG. 5 where the shape of the socket between tangs 40 16 is seen in full lines and the seat required for the tang 12 is shown in dotted lines. The distances x represent the amount of this interference which may vary widely from a few thousandths to as much as $\frac{1}{16}$ of an inch or more in limited areas.

45 With this relative relation of the gun stock and receiver in mind, reference will next be had to the heating of the receiver. While satisfactory results have been obtained by heating the receiver to temperatures within the range of 700° to 900° F., a narrower range of 800° to 825° F. 50 has been found preferable. One method of so heating the receivers is to place them in an electric furnace or oven 20 as indicated in FIG. 1. It has been found that if a group of receivers is left in the oven they will "come up to heat" in about 10 minutes. Preferably the oven heat is set for the higher limit of the above-mentioned 55 preferred range, namely 825° F. so that when brought out for assembly the receiver will not cool below the desired lower limit prior to completion of assembly.

It is convenient at this time to coat the seats of the 60 wooden stocks with a char-retarding compound while waiting for the receivers to be heated. As has been brought out above the present invention involves displacement of wooden fibres by pressing the heated receiver against such seat. It can here be noted that the

65 heats employed are sufficient to char or carbonize the wood but not high enough to ignite it. These temperatures have been found necessary in order to displace the required amount of wood to give proper interfitting of the parts with a minimum of tolerance control of the sizes of such parts. While the use of a char-retarding 70 compound is not vital in all cases, the size or mass of

the steel gun receivers, herein dealt with, is such that acceptable results are obtained only when a char-retarding compound is used. Otherwise uncontrolled charring might result, a condition which would not only show up as a highly objectionable line of discoloration on the finished wooden piece adjacent the contacting areas between the parts but also could detrimentally affect the physical properties of the wood. The use of a char-retarding compound not only prevents objectionable discoloration but also the charred wood which is displaced retains substantially the same physical strength properties so that the resultant product is in fact stronger because of the equal distribution of forces due to the uniform and complete surface contact between the two pieces.

The selection of a char-retarding compound is based on the ability of the material to limit the spread of char and is believed to be the result of a blanketing effect which limits the availability of oxygen to the wood as it is contacted by the heated receiver. Petroleum jelly has been found preferable not only in limiting or controlling char but also because it does not discolor the wood in any objectionable manner. However, other greases, jellies and the like could be employed particularly where discoloration is not of prime importance.

With the seat of the stock 14 coated with petroleum jelly it is ready for assembly with the receiver 10. Preferably a jig such as is seen in FIG. 3 is used. This jig comprises a saddle 18 for receiving the stock 14, when said saddle is in retracted position. The tangs 12 of the heated receiver may be first manually inserted and positioned between the tangs 16, due to the slight taper, as seen in FIG. 5, thereafter the stock is placed in the saddle 18 and the receiver 10 is placed in a fixture 20 in abutting relation to a cross piece 21. A clamp 22 may also be placed over the tangs 16 to prevent spreading when the parts are forceably brought together. The saddle 18 is next advanced along horizontal guide rods 24 by rotation of a jack screw 25 which is threaded into a fixed upright 26 and provided with a handwheel 28 at its outer end. The parts are thus brought to the relative positions seen in FIG. 3 with the tangs 12 firmly seated between the tangs 16 and with the ends of said tangs firmly seated against the stock and receiver respectively to provide the above-mentioned four point bearing which evenly distributes the impact forces involved in firing the gun. By way of further explanation of "four point bearing," charring and displacement of wood fibres occurs most importantly at the ends of the two tangs 16 which are forced against lands, as at 30, on the receiver, and charring and displacement also occurs at the top and bottom of the socket between the tangs 16, as at 32 and 34 (FIGS. 3 and 5).

In passing it will be observed that tongues 36 extend from the tangs 16 in a conventional fashion. These tongues are received by recesses in the receiver to prevent spread of the tangs 16 after assembly.

It will be appreciated that by using the above-described fixture a fair amount of force can be provided in seating the receiver. Experiments have shown that this force should be in the order of 500 to 1,000 pounds for the illustrated stock and receiver. However, the amount of force will vary in relation to the size of parts and the amount of wood to be displaced.

It has also been found that the preferred temperatures are so high and the mass of the receiver so great that the char-retarding effect of the petroleum is only temporary in nature. This is, if the assembled parts are left

untouched, an objectionable charring of the wood is likely to result. Two possible solutions to this problem have been discovered. One is to disassemble the parts immediately after they have been properly seated. It has also been found that this disassembly should be done within 20 to 30 seconds after the parts have been firmly seated. Such disassembly thus involves keeping the stocks and receivers in matching pairs so that they may later be reassembled. For this reason the receiver is preferably cooled by directing a blast of cooling air or other cooling medium on the receiver immediately after proper assembly to prevent undesirable and uncontrolled charring of the wood.

It will, of course, be appreciated that the above-described method could equally as well be carried out by automatic means within the spirit and scope of the present invention.

Having thus described the invention, what is novel and desired to be patented by Letters Patent of the United States is:

1. In the manufacture of firearms the method steps of forming on a wooden stock a seat which is to be fitted with a correspondingly shaped portion of a metal receiver wherein the seat so formed provides an interference of materials with said correspondingly shaped portion, coating said seat with a fluent char-retarding compound, heating said receiver to a temperature of 700°-900° F., and forcing the said correspondingly shaped portion against said seat to form an intimate contact fit therebetween by displacing, compressing and charring the interfering wood portions, the charring action being controlled by the char-retarding compound.

2. In the manufacture of firearms comprising a tanged receiver interdigitated with a tanged stock; the steps of forming on each, seats for receiving the tangs of the other, with an interference of wood on the stock preventing the tangs of each from being fully interdigitated, coating with a char-retarding compound the portions of the stock tangs which are to contact the receiver tangs, heating the receiver to 700-900° F., interdigitating the stock tangs and receiver tangs and seating the receiver tangs against the stock and the stock tangs against the receiver to obtain a four point bearing between the stock and the receiver by compressing and charring said interfering wooden portions of the ends of the stock tangs and the seats of the stock against which the receiver tangs are seated to obtain full interdigititation of the tangs the charring action being controlled by the char-retarding compound and cooling the receiver after obtaining said four point bearing.

3. The method of claim 2 wherein petroleum jelly is used as the char-retarding compound.

4. The method of claim 3 wherein the stock is formed with a seat for receiving the sides, as well as the ends, of the receiver tangs, said seat having an interference preventing free interdigititation with the receiver tangs, the stock and receiver tangs are forcibly interdigitated and the stock tangs are prevented from spreading as they are interdigitated.
